(57) **CLAIM**

The ornamental design for a jewelry box, as shown and described.

DESCRIPTION

FIG. 1 is a perspective view of a jewelry box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is a closed perspective view thereof; and,

FIG. 10 is an enlarged view of the portion labeled "10" encircled in FIG. 6.

The dash-dash broken lines in the drawings depict portions of the jewelry box that form no part of the claimed design.

1 Claim, 10 Drawing Sheets
